UNITED STATES PATENT OFFICE.

CHARLES W. HUBBARD, OF BOSTON, MASSACHUSETTS.

WINDING AND TWISTING APPARATUS.

1,258,411.

Specification of Letters Patent.

Patented Mar. 5, 1918.

Application filed May 3, 1915. Serial No. 25,836.

To all whom it may concern:

Be it known that I, CHARLES W. HUBBARD, a citizen of the United States, residing at Boston, county of Suffolk, State of Massachusetts, have invented an Improvement in Winding and Twisting Apparatus, of which the following description, in connection with the accompanying drawing, is a specification, like characters on the drawing representing like parts.

This invention relates to apparatus for twisting and winding yarn of that type in which the yarn mass is built up in layers extending transversely to the axis of rotation thereof. A winding and twisting apparatus of this type is illustrated in my Patent No. 1,232,685, dated July 10, 1917.

The objects of my present invention are to improve devices of this character by simplifying the construction thereof and making the winding head compact, thus making the apparatus capable of running at an increased speed, and also to provide a novel yarn receiver in the form of a tubular element having a bottom or yarn-supporting member slidable longitudinally therein so that as the yarn mass is built up the yarn support will be forced axially of the yarn receiver, and otherwise to improve winding and twisting apparatus of this nature, all as will be more fully herein-after described and then pointed out in the appended claims.

In order to give an understanding of my invention I have illustrated herein a selected embodiment which will now be described.

Fig. 1 is a vertical sectional view of a spinning and twisting apparatus embodying my invention;

Fig. 2 is a bottom plan view of the holder for the yarn receiver;

Fig. 3 is a vertical section on substantially the line $x-x$, Fig. 4;

Fig. 4 is a section on the line $y-y$, Fig. 1;

Fig. 5 is a section on the line $a-a$, Fig. 1;

Fig. 6 is a section on the line $b-b$, Fig. 1;

Figs. 7 and 8 are fragmentary sectional views showing different forms of yarn supports which may be used in the yarn receiver.

The apparatus herein shown is somewhat similar to that illustrated in my above-mentioned Patent No. 1,232,685, in that it embodies a rotary yarn receiver 1 in which the yarn mass 2 is built up in layers ex-

tending transversely to the axis of rotation by means of a rotary winding plate 3 which rests on the yarn mass and is provided with a yarn-delivery slot 4 through which the yarn 5 is laid by means of a vibrating yarn guide 6, the winding plate 3 rotating at a different speed from the yarn receiver 1 to effect the desired winding action.

In the present embodiment of my invention I have aimed to simplify the mechanism of the twisting head, of which the winding plate 3 and yarn guide 6 form a part, so as to make it capable of high speed operation. The winding plate 3 is shown as secured to the lower end of a member 7 which is provided with a transverse passage or space 8 in which the yarn guide 6 reciprocates, and this member 7 is rigidly secured to a hollow spindle 9 through which the yarn 5 is led to the yarn guide 6 and which is rotated at the proper speed from a gear 10 thereon which may be driven from any suitable source of power. The yarn receiver 1 is connected to and depends from a holding element 11 having a shell-like formation, said holding element being secured to a sleeve or shaft 12 through which the spindle 9 extends and which has fast thereon a gear 13 by which it is driven. This hollow shaft or sleeve 12 is journaled in suitable bearings 14. The gears 10 and 13 are driven from any suitable source and at the desired speeds to give the winding plate 3 and yarn receiver 1 the proper relative speed.

In order to simplify the construction and to provide a device capable of high speed operation I have secured the yarn guide 6 to a rock-shaft 15 which is journaled in the member 7 and extends transversely. Said rock shaft is given its required oscillatory movement by means of a cam member 16 which is loosely mounted on a sleeve 17 that encircles the spindle 9 and is inclosed in the sleeve 12. The cam element 16 is provided with a peripheral cam groove 18 in which is received a roll 19 carried by a slide 20 that operates in a suitable guideway 21 formed in a housing or shell-like member 22 that incloses the cam member 16 and is secured to the member 7, said members 22 and 7 forming a chamber 23 in which the cam 16 is received. This slide 20 is connected at its lower end to a crank arm 24 formed on the rock-shaft 15 so that vertical reciprocating movement of the slide 20 will

oscillate the shaft 15 thereby oscillating the 5
yarn guide 6. The cam groove 18 in the
cam member 16 is so shaped and constructed
that as the cam member 16 rotates relative
to the member 7, the slide 20 will be given
a vertical reciprocating movement. The
cam member 16 is given its rotary move-
ment by differential gearing actuated partly
by the spindle 9 and partly by the shaft 12.
10 The sleeve 17 is shown as having fast there-
to a gear 26 which meshes with a pinion 27
pivotally mounted on the member 7, and this
pinion 27 also meshes with a gear 28 which
runs loose on the sleeve 17 and is fast to
15 the cam member 16. The sleeve 17 is splined
to the hollow shaft 12 and, therefore, rotates
therewith, this being provided for by a key
or spline 29 carried by the sleeve 17 which
operates in a longitudinal groove 30 formed
20 in the hollow shaft 12 interiorly thereof.
Since the gear 26 rotates with the shaft 12
while the gear 27 has a bodily movement
with the member 7 and spindle 9, there will
be a relative movement between these gears
25 which will result in giving rotation to the
gear 28 and cam member 16. The gears 26
and 28 are provided with different number
of teeth so that the oscillating rotary move-
ment of the gear 28 and cam member 16
30 will be faster or slower than the rotation
of the shaft 12 and yarn receiver, depend-
ing on whether the gear 26 has a greater or
less number of teeth than the gear 28. The
parts 22 and 7 fit tightly together so that
35 the chamber 23 is oil tight and thus the
gears 26, 27 and 28 and the cam member 16
can be situated in an oil chamber.

Associated with the yarn guide 6 is a 40
compensating member 33 in the form of a vi-
brating arm having a guide eye 34 at its
end through which the yarn 5 passes in its
transit from the end of the spindle 9 to the
yarn guide 6. This compensating arm has
45 for its function to compensate for the radial
movement of the thread guide 6 so that the
yarn will be drawn through the spindle 9
at a uniform speed notwithstanding the os-
cillating movement of the thread guide 6.
This compensating arm is given its move-
50 ment by mechanism similar to that which
operates the yarn guide 6. Said arm is
shown as fast on a rock shaft 35 mounted
in the member 7 and extending parallel to
the shaft 15, said rock shaft having a crank
55 arm 36 thereon which is pivotally connected
to a slide 37 similar to the slide 20 and op-
erating in a guideway 38 formed in the
member 32. This slide 38 is provided with
a roll 39 operating in a cam groove 40
60 formed in the cam member 16, said cam
groove having such a shape as to give the
compensating arm 33 its requisite move-
ment. In order to make a compact struc-
ture I have placed the cam groove 40 within
65 the cam groove 18. The cam groove 18

is wider than the cam groove 40 and is
of sufficient width so that the groove 40
may be formed in the bottom of the cam
groove 18. This makes a double cam
groove by which both the compensating 70
arm 33 and yarn guide 6 are operated, and
permits the cam member 16 to be of a com-
pact size.

In order that the device may be operated
at a high speed without any undue vibra-
tion it is necessary that it should be thor-
oughly balanced, and to provide for main-
taining an even balance notwithstanding the
reciprocating movement of the thread guide
6 and compensating arm 33, I have provided
80 a transversely-moving member 43 operating
in a suitable guideway and having a projec-
tion 44 operating in a cam groove 45 formed
on the top of the cam member 16. This
cam groove is properly shaped so that the 85
reciprocating movement of the balancing
member 43 will have such a relation to the
vibration of the arms 6 and 33 as to main-
tain the twisting head in true balance at all
times. The twisting head above described 90
is very compact in structure and is well
adapted for high speed operation.

In the structure herein illustrated the yarn
receiver and twisting head have no axial
movement relative to each other during the 95
laying of the yarn mass 2, but the yarn mass
is built up on a yarn support which is
capable of moving axially of the yarn re-
ceiver 1 as the yarn mass accumulates. This
yarn support is shown at 45 and it is con-
structed to have frictional engagement with
100 the walls of the yarn receiver so as to pro-
vide sufficient resistance to the movement of
the yarn mass to insure that the yarn will be
compactly laid. This yarn support 45 may 105
be constructed in various ways without de-
parting from my invention. In Figs. 1 and
6 I have shown it as formed in two sections
46 and 47 which are yieldingly pressed
110 against the walls of the yarn receiver 1 by
means of two springs 48. These sections 46
and 47 may be made of wood or any other
suitable material and both sections are shown
as provided with aligned transverse recesses
49 in which a spring-receiving tube 50 is 115
received, the springs 48 being mounted in
said tubes 50. One end of each spring bears
against the end wall 51 of the recess 49 in
the member 47, and the other end of the
spring bears against the plug 52 screwed into 120
the end of the sleeve 49. Said springs thus
tend to separate the members 46 and 47 and
to yieldingly hold them against the walls of
the yarn receiver 1. This yarn support 45 is
a reversible one and is provided on each face 125
with a layer 53 of felt or similar material
that will furnish a proper frictional anchor-
age for the yarn at the beginning of the
winding operation. As the yarn mass ac-
cumulates, the yarn support 45 is forced 130

downwardly in the yarn receiver 1. The construction I have herein illustrated is such that when the yarn receiver 1 has been filled sufficiently it can be detached from the holder element 11 in order that its place may be taken by an empty yarn receiver. To provide for thus detachably securing the yarn receiver to the holder element 11, the latter is formed at its lower end with the tubular portion 73 which is adapted to detachably engage the upper end of the yarn receiver 1. Said yarn receiver is shown as having at its upper end a band 54 that is adapted to be received within the tubular portion 73, and said band and tubular portion are provided with the well-known bayonet-joint lock.

The yarn receiver 1 is sustained at its lower end in a step bearing to which it is removably secured so that it can be readily disconnected from the bearing when it is filled and it is necessary to remove it from the machine. This step bearing is shown as comprising a cup-shaped member 55 into which the lower end of the yarn receiver 1 may be received and which is carried by a spindle 56 rotatably mounted in a bearing 57 and having at its lower end a step 58 sustained in an anti-friction step bearing 59. This bearing member 57 is received in a supporting element 60 which is mounted for vertical sliding movement in a bearing or guide 61. The member 60 has a roll 62 pivoted thereto which is adapted to engage a lever 63 pivoted at 64, said lever being provided with a weight 69 which is sufficient to hold the cup-shaped member 55 in elevated position. Fig. 1 of the drawings shows this lower step bearing with the member 55 depressed and in the position in which it would be moved in order to disconnect it from the lower end of the receiver 1. The lever 65 is provided with a treadle 67 by which the bearing member can be lowered. The weight of the yarn receiver is taken by the holder 73 and the cup-shaped member 55 is merely a steadyng device to furnish a steadyng bearing for the lower end of the yarn receiver.

When the yarn receiver is filled the treadle 67 will be depressed into the position shown in Fig. 1 thereby removing the cup-shaped member 55 from the lower end of the yarn receiver, and when this has been done said receiver can be disconnected from the holder 73 and removed from the machine.

I have shown in Figs. 7 and 8 two different forms of yarn supports. In Fig. 7 the yarn support comprises the two semi-circular sections 100, 101 which are connected by a spring rod or plate 102 that is connected at its ends, as at 103, to the two sections. This plate tends to assume the straight position shown in Fig. 7, and in this position it holds the sections 100, 101 frictionally against the walls of the yarn receiver 1. In Fig. 8 I

have shown a similar construction except that a separate member 105 is employed on which the yarn mass is built and which is provided with a stem 106 that enters a central aperture in the sections 100, 101 and 102 bears against the resilient plate or rod 102. When pressure is applied to the platform or member 105 the resilient member 102 will be bent slightly, thus drawing the sections 100, 101 toward each other and relieving the friction thereof against the inner walls of the receiver 1.

While I have illustrated herein some selected embodiments of my invention, I do not wish to be limited to the constructional features shown.

I claim:

1. In a device of the class described, the combination with a tubular rotary yarn receiver, of a yarn support in said yarn receiver which is expansible in a direction at right angles to the axis of the yarn receiver and has frictional engagement with the walls thereof, and means to build up a yarn mass on said yarn support in layers extending transversely to the axis of rotation, said yarn support being movable longitudinally of the yarn receiver as the yarn mass is built up.
2. In a device of the class described, the combination with a tubular rotary yarn receiver, of a sectional yarn support within the yarn receiver, springs acting on the sections of said yarn support and holding them in frictional engagement with the walls of the yarn receiver, and means to wind on the yarn support a yarn mass in layers extending transversely to the axis of rotation of the yarn receiver, said yarn support being movable longitudinally of the yarn receiver as the yarn mass is built up.

3. In a device of the class described, the combination with a tubular rotary yarn receiver, of a reversible yarn support in said yarn receiver, said yarn support being expansible in a direction at right angles to the axis of rotation of the yarn receiver and having frictional engagement with the walls of said yarn receiver, and means to wind a yarn mass on said yarn support in layers extending transversely to the direction of rotation of the yarn receiver, said yarn support being movable longitudinally of the yarn receiver as the yarn mass is built up.

4. In a device of the class described, the combination with a winding head provided with a winding plate and a vibrating yarn guide, of a tubular yarn receiver, means to rotate the yarn receiver and winding plate relative to each other, a yarn support within the yarn receiver, said yarn support being expansible in a direction at right angles to the axis of rotation of the yarn receiver and having frictional engagement with the walls thereof, said winding head operating to

build up a yarn mass on said support in layers extending transversely to the axis of rotation and said yarn support being moved longitudinally of the yarn receiver as the 5 yarn mass is built up, the frictional engagement between the yarn support and the yarn receiver holding the yarn mass pressed against the winding plate.

5. In a device of the class described, the 10 combination with a tubular yarn receiver and means to rotate it, of a yarn support within said yarn receiver, which yarn support is expansible in a direction at right angles to the axis of rotation, a winding 15 head for laying a yarn mass on the yarn support in layers extending transversely to the axis of rotation, said winding head embodying a winding plate which rests on the 20 yarn mass, the frictional engagement between the yarn support and the walls of the yarn receiver causing the yarn to be laid compactly and under pressure.

6. In a device of the class described, the 25 combination with a vertically-extending shaft, of a hollow holder mounted thereon, a tubular yarn receiver detachably connected to and depending from said holder, a winding head situated within the holder and having provision for laying yarn in said 30 yarn receiver in layers extending transversely to the axis of rotation, and a step bearing for the lower end of the yarn receiver, said step bearing being movable axially of the yarn receiver to separate it 35 therefrom thereby to permit said yarn receiver to be removed from the holder.

7. In a device of the class described, the 40 combination with a rotatable holder, of a tubular yarn receiver depending from and detachably connected to said holder, a winding head for winding a yarn mass in said 45 yarn receiver in layers extending transversely to the axis of rotation, a bearing for the lower end of the yarn receiver comprising a cup-shaped member in which the lower end of the yarn receiver is removably received, and a vertically-movable bearing in which said bearing member is journaled.

8. In a device of the class described, the 50 combination with a winding head having a winding plate and a vibratable yarn guide, of a yarn receiver, means for causing said winding plate and yarn receiver to have a relative rotary movement whereby yarn will 55 be laid in layers extending transversely to the axis of rotation, and an expansible yarn support situated within the yarn receiver and on which the yarn mass is built up, said yarn support being movable longitudinally 60 of the yarn receiver as the yarn mass accumulates, the expansive action of the yarn support providing a frictional engagement between said yarn support and the walls of the receiver as said yarn support moves longitudinally.

9. In a device of the class described, the combination with a tubular yarn receiver, of a sectional yarn support in said yarn receiver, which yarn support is movable longitudinally of the yarn receiver, springs acting on the sections of the yarn support and holding them in frictional engagement with the walls of the yarn receiver, a winding head having a winding plate and vibrating 70 yarn guide, and means to cause the winding plate and yarn receiver to have a relative rotary movement whereby the yarn will be laid in layers extending transversely to the 75 axis of rotation.

10. In a device of the class described, the 80 combination with a slotted winding plate, of a rotatable element by which said plate is supported, a yarn guide pivoted to said element above the winding plate, a yarn receiver, means to rotate the yarn receiver, and means situated above the yarn guide and actuated partly by the rotative movement of said rotatable element and partly by the 85 rotative movement of the yarn receiver to vibrate the yarn guide.

11. In a device of the class described, the combination with a slotted winding plate, of a rotatable element to which the winding plate is secured and provided with a spindle, a yarn guide pivoted to said element above 90 the winding plate, a yarn receiver, means to rotate said yarn receiver, a cam situated above the yarn guide and rotatable about said spindle, means for vibrating the yarn guide by rotation of the cam, and means to rotate said cam by the combined rotative movement of said element and yarn receiver.

12. In a device of the class described, the 105 combination with a winding plate, of a rotatable element by which said plate is supported, said element being provided with an inclosed chamber, a yarn guide pivoted to said element between said chamber and winding plate, a yarn receiver, means to 110 give the winding plate and yarn receiver a relative rotary movement, and means within said chamber and actuated by said relative rotary movement to vibrate the yarn guide.

13. In a device of the class described, the 115 combination with a slotted winding plate, of a rotatable element by which said plate is supported, a yarn guide pivoted to said element, a compensating member also pivoted to said element, a yarn receiver, means to 120 give the yarn receiver and winding plate a relative rotary movement, and means situated above the yarn guide and actuated by said relative rotary movement for vibrating said yarn guide and compensating member.

14. In a device of the class described, the 125 combination with a vertically-extending shaft, of a holder mounted thereon, a tubular yarn receiver detachably connected to and depending from said holder, a winding 130

head having provision for laying yarn in said yarn receiver in layers extending transversely to the axis of rotation, and a step bearing for the lower end of the yarn receiver, said step bearing being movable axially of the yarn receiver to separate it therefrom thereby to permit it to be removed from the holder.

15. In a device of the class described, the combination with a vertically-extending shaft, of a holder thereon, a yarn receiver depending from and detachably connected

to the holder, a winding head for laying yarn in layers extending transversely to the axis of rotation, a bearing for the lower end 15 of the yarn receiver, which bearing is movable axially of the yarn receiver to separate it therefrom thereby to permit the yarn receiver to be removed from the holder, and means for thus giving said bearing its axial 20 movement.

In testimony whereof, I have signed my name to this specification.

CHARLES W. HUBBARD.
